UNITED STATES PATENT OFFICE.

HARRY ROBERT NORTHOVER, OF WINNIPEG, MANITOBA, CANADA.

MEANS OR APPLIANCE FOR STRIPPING CARTRIDGES FROM CHARGER-CLIPS.

1,355,684.

Specification of Letters Patent. Patented Oct. 12, 1920.

Application filed March 5, 1918. Serial No. 220,668.

To all whom it may concern:

Be it known that I, HARRY ROBERT NORTHOVER, a subject of the King of Great Britain, and resident of Winnipeg, Manitoba, Dominion of Canada, have invented certain new and useful Improvements in Means or Appliances for Stripping Cartridges from Charger-Clips, of which the following is a specification.

10 It is now the general practice for small-arms ammunition to be issued to troops on service in charger-clips, so that when such ammunition is required to be used for filling Lewis gun and similar magazines, machine-gun belts and strip-chargers and the like, the cartridges have to be removed from the clips before they can be placed in the hopper or cartridge receptacle of the magazine or belt-filling machine. This stripping of 15 the cartridges from charger-clips is an operation which at present has to be performed by hand, and which is liable to involve the loss of valuable time when magazines, belts, or the like, have to be filled in the field.

20 The object of the present invention is to obviate or avoid this disadvantage, and it consists in an arrangement or means which is capable of being applied to or combined with any magazine, belt, or like filling machine, 25 and which enables cartridges to be mechanically stripped or removed from their charger-clips direct into the hopper or like cartridge-receptacle of the machine, and also effects the mechanical ejection of the empty 30 clips, thereby enabling cartridges to be supplied to the said machine as fast as a man can place the clips of ammunition in the stripper.

While, as already stated, the invention is 35 capable of application to any machine for filling machine-gun magazines, belts, strip-chargers and the like, I propose to describe the same, by way of example, in its application to the cartridge-supply system of a machine for filling the magazines of Lewis guns 40 of the kind described in the specification of my application for Letters Patent Serial No. 176863; reference being had to the accompanying drawings, in which—

50 Figure 1 is an elevation of the said Lewis magazine filling machine, to the cartridge hopper of which is applied a mechanical car-

tridge-stripper and clip-ejector in accordance with the present invention.

Fig. 2 is a sectional elevation of the cartridge-stripper part of the machine, showing a clip of ammunition positioned therein, ready for the cartridges to be transferred into the hopper.

Fig. 3 is a sectional elevation similar to Fig. 2, but on a larger scale, and showing how a clip of ammunition is introduced laterally into the appliance.

Fig. 4 is another view like Fig. 3, but it shows the cartridges stripped from the clip and being guided into the hopper of the machine, and it also shows how the empty clip is ejected after the cartridges have been removed therefrom.

Figs. 5 and 6 are two sectional views taken respectively on the dotted lines α and α' , Fig. 2, showing how the clip is positioned in the machine during the cartridge-stripping operation.

Fig. 7 is a section of Fig. 3 on the dotted line α'' .

The same letters of reference indicate corresponding parts in the several figures of the drawings.

The Lewis-magazine filling machine shown in Fig. 1 embodies a cartridge hopper or receptacle a , and the side of the said hopper into which the head ends of the cartridges are delivered, prior to being fed into the magazine, is provided with an upright cartridge-guide b , consisting of a channel-sectioned casting whose internal sectional shape conforms approximately to the shape of the head end of the cartridge. The inner side of this guide is open and its arrangement is such that when the head ends of cartridges are introduced into the upper end thereof, the said cartridges will fall by gravity down the guide in the manner shown in Fig. 4 and will thereby be delivered or directed into the hopper.

According to the present invention, the means for stripping ammunition from clips into the cartridge-guide of the hopper, and for ejecting the empty clips, are provided or arranged in the upper part of the said hopper. That is to say, there is formed in the outer side of the upper part of the cartridge guide b , an aperture or opening c , of

a size and shape suitable to enable a clip of cartridges to be introduced, with the bullet ends of the cartridges leading, laterally thereto, as shown in Fig. 2, and the inter-
 5 nal space between the webs b^1 , b^2 , of the channel-sectioned guide is wide enough to admit the wings d^1 , d^2 , of the clip d but it is narrower than the back d^3 of the said clip, so that when the full clip is pressed right
 10 home into the aperture c ; (as shown in Fig. 2) the side beadings that exist at d^4 , d^5 , on the clip take their abutments against the outer edges of the said webs b^1 , b^2 , of the guide, as shown in the cross section Fig. 4.
 15 Further, after the lateral insertion of the full clip and when the beadings find their bearing against the edges of the webs as above stated, the said clip is slightly lowered, which brings the bottom edges of the side
 20 wings and beadings onto abutments or clip supporting shoulders e that are formed on the inner faces of the webs b^1 , b^2 . In this manner, the clip is positioned and firmly supported inside the guide (see Fig. 2) in
 25 a way that the head ends of the cartridges held in the said clip come over or register with the open-sided channel which leads down to the cartridge hopper of the machine.
 30 For stripping or displacing the cartridges downwardly from the clip into the guide (so that they may drop thence by gravity into the hopper) the head f of the guide member is fitted with a spring-influ-
 35 ened plunger g , whose stem g^1 extends through the said head into the aperture c as shown in Fig. 4, but is normally held clear of the cartridge-way by the action of the lifting spring g^2 , the said stem being so
 40 disposed that, after a clip of cartridges has been introduced and positioned in the machine, the base or foot of the plunger comes immediately above the base end of the uppermost cartridge as shown in Fig. 1, so
 45 that on the said plunger being pressed smartly down, it will force the cartridges out of the clip as shown in Fig. 4.
 To effect the ejection of the empty clip after the cartridges have been stripped
 50 therefrom, a lever h is pivoted at h^1 in an open-sided slot or clearance h^2 in the cartridge-guide head. The upper limb h^3 of this lever extends above the said bead and lies in the path of movement of the knob
 55 g^3 on the stripping-plunger, while the lower limb h^4 depends below the slot h^2 into the aperture c ; the lever being influenced by a spring i which normally maintains the same in the position shown in Fig. 3 so that, on a
 60 clip of ammunition being introduced and positioned in the aperture, its beading d^4 will come against the edge of the lower limb h^4 of the said lever as shown in Fig. 4 and in the sectional view Fig. 6, while when the
 65 stripping plunger is operated, and after it

has been depressed sufficiently to strip all the cartridges out of the clip, its knob g^3 will come into contact with the upper limb of the ejector lever and rock or trip the latter into the position indicated in dotted lines in Fig. 70 4, which causes the lower limb, as it swings outward, to eject the clip through the aperture.

Pressure on the stripping plunger being then relieved, the plunger and ejector springs 75 function to restore the plunger and ejector to the positions shown in Fig. 3; leaving the appliance ready for the reception of the next full clip.

It is to be understood that the scope of 80 my invention includes any arrangement that will temporarily support a clip of cartridges above a guide or the like leading to a hopper or similar cartridge receptacle, and any plunger or equivalent device for stripping the 85 cartridges out of the said clip and then operating or transmitting suitable motion to a device for ejecting or throwing out the empty clip; and that the application of my invention to machines for filling cartridge- 90 magazines other than of the Lewis gun type, or for filling machine-gun belts, strip-chargers and the like, differs in no essential respect from its application to a Lewis magazine filler as herein described. 95

This application is a continuation in part of my former application, Serial Number 176,863, filed June 25, 1917, Patent No. 1,313,727, dated August 19, 1919.

Having now described my invention, what 100 I claim and desire to secure by Letters Patent is:—

1. The combination with a device for supporting clipped ammunition and positively stripping the cartridges therefrom, of a device, operated from the cartridge-stripper for ejecting the empty clip. 105

2. A device of the character described, comprising a cartridge-guide having, in one side, an aperture or opening wherethrough a clip of cartridges may be introduced, said aperture being formed with seatings for supporting or positioning the clip, and said cartridge-guide being provided, above the aperture with manually-operated 110 means whereby cartridges are stripped from the positioned clip, and a device operated by said means for ejecting the empty clip through the aperture after the stripping of the cartridges has been effected. 115

3. A device of the character described, comprising a cartridge-guide having, in one side, an aperture or opening wherethrough a clip of cartridges may be introduced, said aperture being formed with seatings for supporting or positioning the clip, and said cartridge-guide being provided, above the aperture with the manually-operated means whereby cartridges are stripped from the positioned clip, a device operated by said means 120

125

for ejecting the empty clip through the aperture after the stripping of the cartridges has been effected, said cartridge-stripping device consisting of a spring-retumed depressible plunger, and a clip ejector consisting of a pivoted limb, which engages the clip when the latter is positioned in the car-

tridge-guide, and is adapted to be operated from the said plunger, substantially as herein described.

10

In testimony whereof I have signed my name to this specification.

HARRY ROBERT NORTHOVER.
